UNITED STATES PATENT OFFICE

121,475

DESIGN FOR A COMBINED BLOTTER AND HOLDER THEREFOR

Joseph Komorous, Riverside, Ill.

Application May 1, 1940, Serial No. 92,063

Term of patent 14 years

To all whom it may concern:

Be it known that I, Joseph Komorous, a citizen of the United States, residing at Riverside, in the county of Cook and State of Illinois, have invented a new, original, and ornamental Design for a Combined Blotter and Holder Therefor, of which the following is a specification, reference being had to the accompanying drawing forming part thereof.

In the drawing:

Fig. 1 is a top plan view of a combined blotter and holder therefor, showing my new design.

Fig. 2 shows one of the sides, both of which are identical.

Fig. 3 is a bottom plan view.

Fig. 4 is an end view of the same, the two ends being identical.

I claim:

The ornamental design for a combined blotter and holder therefor, as shown and described.

JOSEPH KOMOROUS.
